UNITED STATES PATENT OFFICE.

JOHN O. MCKEAN, OF WESTFIELD, MASSACHUSETTS, ASSIGNOR TO FOSTER MACHINE COMPANY, OF WESTFIELD, MASSACHUSETTS, A CORPORATION OF MASSACHUSETTS.

YARN-TENSION DEVICE.

Application filed October 21, 1921. Serial No. 509,250.

To all whom it may concern:

Be it known that I, JOHN O. MCKEAN, a citizen of the United States, and resident of Westfield, in the county of Hampden and 5 State of Massachusetts, have invented a new and useful Improvement in Yarn-Tension Devices, of which the following is a specification.

In stop motions, in connection with which 10 a tension device is used which includes a loosely mounted gravity operated tension disk, the disk has, so far as known, been pre-made of cast iron or machine steel, thus presenting a hard metal yarn contact surface. 15 Therefore, when the stop motion operates, the dropping of the arm on which the tension device is mounted causes a sharp hammer blow of the hard metal yarn contact surface of the disk on the yarn located between the disk and its support, frequently 20 cutting the yarn in two.

The object of my invention is to prevent this cutting action of the disk, by providing a disk having a soft or malleable metal surface 25 face contacting with the yarn, either by providing a built-up tension disk having an insert of soft or malleable metal, such as lead for example; or by providing an integral disk composed of a soft or malleable 30 metal.

Practical embodiments of my invention are represented in the accompanying drawings, in which—

Fig. 1 illustrates, in side elevation, the 35 portion of a stop motion which carries the tension device, including my improved gravity operated loosely mounted tension disk, the parts being shown in dotted lines in their normal running position, and in full 40 lines in their "knocked off" or "stopped" position.

Fig. 2 illustrates one form of tension disk in top plan.

Fig. 3 illustrates the same in bottom plan.

Fig. 4 illustrates the same in side elevation.

Fig. 5 illustrates the same in vertical central section.

Fig. 6 illustrates another form of tension 50 disk in side elevation.

Fig. 7 illustrates the same in vertical central section.

The tension device includes the yarn sup-

port 1 carried by the swinging arm 2 of the stop motion, from which support 1 55 rises a pin 3, as is usual. Loosely mounted on the pin 3 is a gravity operated tension disk which normally rests upon the yarn support 1. The yarn, indicated by 4, passes 60 between the support 1 and the gravity operated tension disk.

In the built-up form of tension disk, illustrated in Figs. 1 to 5 inclusive, a soft or malleable metal insert 5 is permanently secured to the face of a lateral flange 6 65 extending from a hollow sleeve 7. This is preferably accomplished by spinning the edge 8 of the flange 6 into the periphery of the insert 5. This insert is provided with a central hole 9 in alinement with the bore 70 of the sleeve 7.

In the integral form of tension disk, illustrated in Figs. 6 and 7, the disk 10 is composed of soft or malleable metal, and it is provided with a centrally arranged hole 11 75 for loosely mounting the disk on the pin 3.

The soft or malleable metal which I have found suitable is lead. By providing a soft or malleable metal yarn contact surface for the tension disk, I have found that no 80 amount of hammering blow, due to the operation of the stop motion, is sufficient to cut the yarn, thus rendering the tension disk particularly well adapted for use in connection with yarn tension devices which are 85 mounted on stop motions where the tension devices are subjected to violent movements due to the operation of the stop motion.

It is evident that various changes may be 90 made in the construction, form and material of the tension disks without departing from the spirit and scope of my invention; hence I do not wish to limit myself to the particular embodiments illustrated but

What I claim is:

1. A tension disk having a yarn contact surface of a metal having substantially the softness of lead.
2. A tension disk having a lead yarn contact surface.
3. A tension disk of a metal having substantially the softness of lead.
4. A lead tension disk.
5. In a tension device, a suitable support, a vertically disposed pin, and a gravity operated tension disk loosely mounted on the

pin, said disk having a yarn contact surface of a metal having substantially the softness of lead.

6. In a tension device, a suitable support, 5 a vertically disposed pin, and a gravity operated tension disk loosely mounted on the pin, said disk having a lead yarn contact surface.

7. In a tension disk, a suitable support, 10 a vertically disposed pin, and a gravity op-

erated tension disk of a metal having substantially the softness of lead loosely mounted on the pin.

8. In a tension disk, a suitable support, a vertically disposed pin, and a gravity operated lead tension disk mounted on the pin. 15

In testimony that I claim the foregoing as my invention, I have signed my name this 13th day of October, 1921.

JOHN O. McKEAN.
